UNITED STATES PATENT OFFICE.

ADAM N. LUTZ, OF SANDUSKY, OHIO, ASSIGNOR OF ONE-HALF TO EDWARD J. ROSINO,
OF SANDUSKY, OHIO.

CORPSE-SUPPORTING REST.

Application filed July 9, 1926. Serial No. 121,285.

In the arrangement of bodies of corpses in caskets preparatory to burial, and especially where the bodies have been embalmed as is the common practise today, difficulty 5 is experienced in arranging a corpse in a position of natural repose, as is so frequently requested by the family of the deceased.

With the foregoing in view, one of the purposes of the present invention is to provide 10 an attachment or device which may be placed in the casket to support the body of the corpse above the casket, and which involves adjusting features that permit of raising the head and sides of the body in a number of different ways so as to obtain a 15 nearly life-like attitude of repose. A second purpose of the invention has been to devise a body adjusting device of the general type referred to, which not only is useful 20 to support the body of a corpse in the casket, but will be susceptible of advantageous use as a means to hold the body during the process of embalming, supporting the corpse under such conditions so that when 25 ultimate rigidity takes place, the corpse will not be difficult to place in a natural life-like attitude when arranged in the casket subsequent to the embalming.

More specifically, the invention involves 30 an adjustable rest device involving an upper body support, a head support and a side adjusting support all arranged in a compact structure susceptible of folding and with the parts readily adapted to be covered 35 by the lining, cloth or silk or other material, in the casket, when the device is employed with the latter. The construction is one which is relatively inexpensive also and may be retained within the casket when it 40 is buried with the corpse.

A full understanding of the invention will be had upon reference to the following detailed description, and to the accompanying drawings, in the latter of which:—

45 Figure 1 is a side view of a common type of casket showing the corpse disposed therein and about one-half of the casket being broken away and illustrated in section to disclose the arrangement of my device in 50 supporting relation to the corpse.

Figure 2 is a detailed perspective view of the adjustable rest device alone.

Figure 3 is a cross sectional view taken about on the line 3—3 of Figure 2, looking in the direction of the arrows.

Describing the invention specifically, in conjunction with the drawings, A denotes the casket illustrated which may be of any conventional type at present in use. It is unnecessary to refer to conventional methods of burial but at B is shown the corpse which is to be buried in the casket as used. The casket A is equipped with the usual lining C and it is contemplated to place the adjustable rest of this invention beneath said lining.

Referring particularly to Figure 2, it is notable that the adjustable rest device comprises a main or base frame 1 upon which is mounted a pivoted adjustable supporting frame 2, the points of pivotal connection being located at 3. As a means for holding the adjustable frame 2 in different positions I provide pivoted dogs 4 which are adapted to engage in anyone of the series of notches 5 provided longitudinally of the sides of the frame 2 near the ends opposite the pivotal connections 3.

Mounted upon the adjustable frame 2 is the adjustable head rest 6 which consists of 80 side members pivotally connected at 7 to the sides of the adjustable frame 2. The sides of the head rest 6 are connected by a cross piece 8 hingedly attached at 9 to said sides. A flexible apron or support 10 also connects 85 the free ends of the sides of the head rest 6 at a point adjacent to the connection of the cross piece 8. The purpose of the apron 10 is to give a relatively large area of support adjacent to the piece or head portion of the 90 corpse in the manner typified by the illustration of Figure 1. In order to support the head rest 6 at different adjustments as required I use ratchet members 11 pivoted to the sides of the head rest 6 and said ratchet 95 members engage the transverse rod 12 carried by the sides of the frame 2.

Another reason for providing the cross-piece 8 hingedly connected with the sides of the rest 6, and the apron 10 affording a flexi- 100

ble connection, is to enable either side of the rest 6 to be raised or adjusted higher or lower than the other side. This is necessary and advantageous if the most natural postures are to be given to the head portion of the corpse in arranging it in the casket.

At the middle portion of the rest device of my invention, I provide an upper body rest 13 which is made practically the same as the rest 6 so that the parts are similarly designated and do not require description other than that just given. The intention is by the construction of the middle body rest to enable one side of the body at the waist and shoulder portions to be elevated or lowered a slightly greater distance as may be required, than the other side. Owing to the flexibility of the connection between the sides of the rests 6 and 13 quite a few different adjustments of the various portions of the said rests may be obtained.

Having in view the foregoing description, it is only necessary to indicate that the structure of my rest device may be collapsed so that the adjustable frame 2 may rest down in and upon the base frame 1, and the rest frames 6 and 13 may be folded down within the frame 2 so that the apparatus is practically flat and occupies a very minimum amount of space when not being used. Obviously the rest device is susceptible of employment by the undertaker and embalmer to assist him in holding or supporting the corpse as the embalming process is performed. I do not wish to be limited to the specification, size or proportions of my device as shown because these may be modified to a considerable extent under practical conditions of manufacture and use. Moreover, while I may construct my device of metal or wood, I wish it understood that I may have recourse to various kinds of materials, so far as this phase of the practical embodiment of this invention is concerned.

Having thus described my invention, what I claim as new and desire to secure by Letters Patent of the United States, is:—

1. In an adjustable rest device such as described, a main base frame, a main adjustable supporting frame carried by the base frame, and another rest frame having side members pivoted within said main adjustable rest frame, the main adjustable rest frame and the rest frame carried thereby being adjustable so that opposite ends thereof will be elevated or lowered by their adjustment, and means to hold the two rest frames in adjusted positions.

2. In an adjustable rest device such as described, a main base frame, a main adjustable supporting frame carried by the base frame, and another rest frame carried by said main adjustable rest frame, the main adjustable rest frame and the rest frame carried thereby being adjustable so that oppo-

site ends thereof will be elevated or lowered by their adjustment, and means to hold the two rest frames in adjusted positions, one of said rest frames being pivoted entirely within the other so that they may become readily collapsed and folded together.

3. An adjustable rest device for the purpose described, comprising a main base frame, a main adjustable supporting frame pivoted near one end to the base frame, and a plurality of successively disposed secondary rest frames pivotally mounted on the main rest frame and adapted to be inclined by their adjustment thereon in a direction opposite to the inclination of the main rest frame.

4. An adjustable rest device for the purpose described, comprising a main base frame, a main adjustable supporting frame pivoted near one end to the base frame, and a plurality of successively disposed secondary rest frames pivotally mounted at one end on the main rest frame and adapted to be inclined by their adjustment thereon in a direction opposite to the inclination of the main rest frame, the said secondary rest frames comprising sides, and flexible means connecting the sides together, together with adjusting devices for the several rest frames.

5. In a rest device, a main base frame, a main supporting frame pivoted thereto to incline in one direction when adjusted thereon, and separately mounted secondary rest frames carried by the main rest frame and pivoted thereto to incline in a direction thereon opposite to the direction of inclination of their supporting rest frame.

6. In a rest device, a base frame, a main pivoted supporting frame carried thereby, a headrest adjustable on the said adjustable frame, and an independent middle body rest also adjustable on said adjustable frame.

7. In a rest device, a base frame, a main pivoted supporting frame carried thereby, a head rest adjustable on the said adjustable frame, and a middle body rest also adjustable on said adjustable frame, the head frame and middle body rests comprising sides pivoted to the rest frame and flexible aprons connecting said sides.

8. An adjustable rest device for the purpose described, comprising a main base frame, a supporting frame pivoted to the base frame, and a plurality of rest frames independently mounted on the supporting frame.

9. An adjustable rest device for the purpose described, comprising a main base frame, a main adjustable supporting frame pivoted to the base frame, and a plurality of rest frames independently mounted and separately adjustable on the supporting frame.

10. An adjustable rest device for the purpose described, comprising a main base

frame, a main supporting frame attached to the base frame, and a rest frame mounted on the supporting frame, said rest frame including side members which are independently adjustable with respect to the supporting frame.

11. An adjustable rest device for the purpose described, comprising a main base

frame, a main adjustable supporting frame pivoted to the base frame, independently adjustable means on each side of said supporting frame for holding it in position, and rest frames carried by said supporting frame.

In testimony whereof I affix my signature.

ADAM N. LUTZ.
